GEARING CONTROL FOR DRILLING
MACHINE TRUCKS OR THE LIKEArthur L. Lee, Upper Arlington, Ohio, assignor to
The Jeffrey Manufacturing Company, a corpora-
tion of Ohio

Application April 6, 1949, Serial No. 85,849

3 Claims. (Cl. 180—53)

1

This invention relates to a truck, particularly adapted to support a drilling machine, mining machine, or other mechanism, for operation in a coal mine.

An object of the invention is to provide an improved truck of the above mentioned type.

A more specific object of the invention is to provide a truck with a primary electric driving reversible motor which drives a gear train leading to traction wheels of the truck and also drives a cable reel and in addition a hydraulic pump; there being shiftable gearing in said gear train, the arrangement being such that the hydraulic pump is driven at all times when the motor is running, and the cable reel is driven whenever the traction wheels are driven, it being possible to drive the cable reel without driving the traction wheels, and also possible to disengage the cable reel drive and the traction wheel drive simultaneously.

Other objects of the invention will appear hereinafter, the novel features and combinations being set forth in the appended claims.

In the accompanying drawings,

Fig. 1 is a plan view of a truck, including the features of my invention, supporting a mining mechanism in the form of a mining drill;

Fig. 2 is a side elevational view of the mechanism of Fig. 1;

Fig. 3 is an enlarged sectional view taken on the line 3—3 of Fig. 1, looking in the direction of the arrows; and also a view on the line 3—3 of Fig. 5;

Fig. 4 is a sectional view taken on the line 4—4 of Fig. 3, looking in the direction of the arrows; and

Fig. 5 is a sectional plan view of the transmission gearing with the associated pump shown in plan.

Referring particularly to Figs. 1 and 2 of the drawings, the truck includes a main frame 10 having a pair of front steering wheels 11, 11 operable from the rear platform 12 of the main frame 10 by a steering wheel 13. Rear traction wheels 14 are provided for the truck, said wheels 14 being driven through conventional gearing, including a differential 15, through appropriate gearing in a gear box 16 which is disclosed in detail and described hereinafter.

The rear platform 12 carries a reversible electric primary driving motor 17, to the rear of which is a cable reel 18 having a conventional spooling device 19 therefor. The cable reel 18 and spooling device 19 are driven from the motor

2

11 through the gear box 16 and gearing therein, as hereinafter described.

Mounted adjacent the front of the main frame 10 there is hydraulic mining transmission illustrated as a hydraulic drill 20 which may, for example, follow the disclosure of the application of John S. Beltz, Serial No. 769,358, filed August 19, 1947, for an Improvement in a Power Driven and Controlled Coal Mine Drilling Machine.

10 Mounted on the housing of the gear box 16 there is a hydraulic pump 21 which supplies hydraulic fluid under pressure to any desired mechanism and in the particular instance to various hydraulic motors of the drill 20. It is obvious that other types of mechanisms may be supported by the main frame 10 of the truck. It is also evident that hydraulic pressure from the pump 21 may be utilized on the truck itself, as distinguished from the drilling mechanism thereon.

Attention is now directed particularly to Figs. 1, 3, 4 and 5 and to the construction of the gearing within the gear box 16 and its association with the reversible primary driving motor 17, the traction wheels 14, the cable reel 18, and the pump 21, since said motor 17 drives the other mentioned devices. Motor 17 is connected through a flexible coupling (see Fig. 1) to a stub shaft 22 (see Fig. 5) mounted in appropriate anti-friction bearings in the gear box 16 and having at one end a bevel gear 23 which meshes with a ring gear 24. Ring gear 24 is rigidly attached to a sleeve or hollow hub 25 which is mounted for free rotation on a drive shaft 26, there being anti-friction bearings interposed between opposite ends of the sleeve 25 and the drive shaft 26.

At its forward end drive shaft 26 extends through a packed opening in the gear box 16 and is connected by a flexible coupling to the differential 15 which leads by appropriate standard gearing to the two traction wheels 14. In other words, the two wheels 14 are differentially driven from the motor 17 through gearing which 40 includes the drive shaft 26. Near its forward end shaft 26 is mounted by an anti-friction bearing in a removable cap of the gear box 16. A sleeve 27 surrounds the shaft 26 and is slidably mounted along the longitudinal axis thereof.

45 Said sleeve 27 is slidably carried on the shaft 26 by a sleeve bushing 28.

At its forward end, as viewed in Fig. 5 of the drawings, the sleeve 27 has a feathered or splined connection with the sleeve 25 as provided by the cooperating splines 29. The cooperating splines

29 thus provide a continuous driving connection between sleeves 25 and 27, while providing for the axial shifting of said sleeve 27 relative to the shaft 26 and the sleeve 25.

Substantially adjacent the center of sleeve 27 and just to the right of the bushing 28, said sleeve 27 is provided with clutch jaws 30 adapted to cooperate with clutch jaws 31 formed integral with the shaft 26. Thus when the sleeve is moved to the right, as viewed in Fig. 5 of the drawings, the clutch elements 30 and 31 will provide a driving connection between the sleeve 27 and the shaft 26. This will, of course, effect a driving connection between the motor 17 and the traction wheels 14 through the differential 15 by way of shaft 22, gears 23 and 24, sleeves 25 and 27, jaw clutch members 30 and 31, and shaft 26.

Intermediate its ends and on the outside thereof the sleeve 27 carries a wide spur gear 32 which is in mesh with a reach gear 33 for all longitudinal or axial positions of adjustment of the sleeve 27. Reach gear 33 is supported by anti-friction bearings on an appropriate shaft 34 in the gear box 16 and meshes with the driving pinion 35 on the drive shaft of the hydraulic pump 21.

It is thus evident that there is a positive drive between the shaft 22 and the pump 21 at all times regardless of the position of the shiftable or adjustable sleeve 27; so the pump 21 is always operating whenever motor 17 is running. Well known valve means may be provided so that the output of the pump 21 is always the same, regardless of its direction of rotation, if desired.

Adjacent its left-hand end, as viewed in Figs. 4 and 5 of the drawings, the shaft 26 extends into a rotatable but nonshiftable sleeve 36 which is mounted in an anti-friction roller bearing carried by a removable partition 37 of the gear box 16. At opposite ends of the sleeve 36 there are anti-friction bearings interposed between the internal surface thereof and the adjacent portion of the shaft 26. To the right of the partition 37 the sleeve 36 has a pair of axially spaced-apart peripheral clutch jaws 38 and 39 adapted to intermesh selectively with jaws 40 carried on a removable ring which forms the left-hand part of the sleeve 27. The jaws 40 may also selectively be adjusted to a position intermediate the jaws 38 and 39, as illustrated in Fig. 4 of the drawings, which is a neutral position for the sleeve 27.

At its left-hand end the sleeve 36 is provided with a bevel gear 41 which meshes with a ring gear 42 of a free wheeling or over-riding roller type clutch 43 which is mounted on a shaft 44, mounted near opposite ends in anti-friction bearings carried by removable caps of the gear box 16. The shaft 44 extends through one of the mentioned caps, adjacent which there is a stuffing box. Said shaft 44 carries a sprocket wheel 45 which is connected by a well known form of gearing, such as a drive chain, to drive the cable reel 18 and the spooling device 19.

Referring particularly to Figs. 3 and 4 of the drawings, it will be seen that manually operated mechanism is provided for shifting the sleeve 27 into any of three positions. This mechanism includes an operating lever 46 having a releasable detent associated with a knob 47. The lever 46 is keyed to an operating shaft 48 which is journaled in a top plate of the gear box 16 and is provided at its bottom with an integral crank arm 49 having a dog or projection 50 extending into an opening in the longitudinally slidable shipper 51. The shipper 51 is mounted in ap-

propriate guideways carried by the gear box 16 and has a pair of downwardly extending arms or projections 52 (see Fig. 4) which straddle the gear 32.

It is evident that by placing the arm 46 in its central position the sleeve 27 will be in the neutral position illustrated in Fig. 4 of the drawings. The sleeve 27 may be shifted either to the right or to the left from its neutral position, as desired by the operator who may manipulate the control lever 46 and latch said lever in any of its three positions.

The gearing within the gear box 16, as above described, is such that under all conditions the hydraulic pump 21 is directly connected to the motor 17, so hydraulic fluid will be produced by said pump 21 whenever the motor 17 is running. If the lever 46 is shifted so as to move the sleeve 27 to the right, said sleeve 27 will be in the position illustrated in Fig. 5 of the drawings. Under these conditions, jaws 30 and 31 will be engaged, as will jaws 39 and 40. Consequently, motor 17 will be connected to drive the traction wheels 14 and to drive the cable reel 18 as this driving operation is modified by the over-run or free-wheeling clutch 43.

If the motor 17 is operated in a direction to drive the truck forward or to the right, as viewed in Figs. 1 and 2 of the drawings, the ring gear 42 of the clutch 43 will be rotated in a counter-clockwise direction at a speed which will allow the cable to rotate the drum 18 so as to feed out said cable. This is because of the fact that the ring gear 42 will rotate faster than the shaft 44, they both rotating in the same direction. Should the motor 17 be reversed so as to move the truck in a reverse direction or to the left, as viewed in Figs. 1 and 2, the cable reel would operate in a reverse direction, namely, to reel in the cable. Said clutch 43 would effect a temporary direct connection between the ring gear 42 and shaft 44, the two rotating in a clockwise direction.

Under some conditions it is desirable to reel in or pay out the cable while the truck is standing still. To do this, sleeve 27 is shifted by the lever 46 so that the clutch jaws 40 on the left-hand thereof mesh with the clutch jaws 38 (see Fig. 4) of the sleeve 36. Under these conditions the jaws 30 and 31 are, of course, disengaged so there is no driving connection to the traction wheels 14. It is then possible to operate the motor 17 in either direction so as to provide for manual paying out of the cable or the reeling in thereof, the action being similar to that when the truck is being driven.

By reference particularly to Fig. 4 of the drawings it will be evident that when the sleeve 27 is in its neutral position the clutch jaws 40 as well as the clutch jaws 30 are disengaged and consequently neither the shaft 26 nor the sleeve 36 are driven, the only drive under these conditions being from the motor 17 to the pump 21.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A truck including a frame, traction means for said frame, hydraulically operated mechanism on said frame, means for driving said traction

means including an electric motor, a hydraulic pump operable to supply fluid pressure for operating said mechanism, a cable reel on said frame, and adjustable gearing selectively interconnecting said electric motor with said cable reel and selectively simultaneously connecting it with said traction means or not as desired, and always interconnecting said electric motor and said pump, said adjustable gearing including a sleeve, gears connecting said sleeve to be driven whenever said motor operates, a shiftable sleeve connected to be driven at all times by said first sleeve and shiftable axially into two driving positions and a neutral position, gearing interconnecting said shiftable sleeve and said pump for all adjustable positions of said shiftable sleeve, gearing connected to said cable reel including a pair of spaced clutch members, said shiftable sleeve having a clutch member adapted to engage selectively one or the other of said pair of clutch members when in either of its two driving positions and to engage neither of them when in its neutral position, a one way clutch in said cable reel drive gearing, gearing connected to said traction means, and traction gearing driving clutch means carried in part by said traction means gearing and in part by said shiftable sleeve and operable to provide a driving connection between said electric motor and said traction means when said shiftable sleeve is in one driving position, in which one driving position a driving connection is also provided by the first named clutch means on said shiftable sleeve and one of said pair of clutch members, said traction gearing driving clutch means being disengaged when said shiftable sleeve is in its neutral position and when it is in the other of its driving positions.

2. A truck including a frame, traction means for said frame, hydraulically operated mechanism on said frame, means for driving said traction means including an electric motor, a hydraulic pump operable to supply fluid pressure for operating said mechanism, a cable reel on said frame, and adjustable gearing selectively interconnecting said electric motor with said cable reel and selectively simultaneously connecting it with said traction means or not as desired, and always interconnecting said electric motor and said pump, said adjustable gearing including a sleeve, gears connecting said sleeve to be driven whenever said motor operates, a shiftable sleeve connected to be driven at all times by said first sleeve and shiftable axially into two driving positions and a neutral position, gearing interconnecting said shiftable sleeve and said pump for all adjustable positions of said shiftable sleeve, gearing connected to said cable reel including a pair of spaced clutch members, said shiftable sleeve having a clutch member adapted to engage selectively one or the other of said pair of clutch members when in either of its two driving positions and to engage neither of them when in its neutral position, gearing connected to said traction means, and traction gearing driving clutch means carried in part by said traction means gearing and in part by said shiftable sleeve and operable to provide a driving connection between said electric motor and said traction means when said shiftable sleeve is in one driving position, in which one driving position a driving connection is also provided by the first named clutch means on said shiftable sleeve and one of said pair of clutch members, said traction gearing driving clutch means being disengaged when said shiftable sleeve is in its neutral position and when it is in the other of its driving positions.

gearing and in part by said shiftable sleeve and operable to provide a driving connection between said electric motor and said traction means when said shiftable sleeve is in one driving position, in which one driving position a driving connection is also provided by the first named clutch means on said shiftable sleeve and one of said pair of clutch members, said traction gearing driving clutch means being disengaged when said shiftable sleeve is in its neutral position and when it is in the other of its driving positions.

3. A truck including a frame, traction means for said frame, hydraulically operated mechanism on said frame, means for driving said traction means including an electric motor, a hydraulic pump operable to supply fluid pressure for operating said mechanism, a cable reel on said frame, and adjustable gearing selectively interconnecting said electric motor with said cable reel and selectively simultaneously connecting it with said traction means or not as desired, and always interconnecting said electric motor and said pump, said adjustable gearing including a sleeve, gears connecting said sleeve to be driven whenever said motor operates, a shiftable sleeve connected to be driven at all times by said first sleeve and shiftable axially into two driving positions and a neutral position, gearing interconnecting said shiftable sleeve and said pump for all adjustable positions of said shiftable sleeve, gearing connected to said cable reel including a pair of spaced clutch members, said shiftable sleeve having a clutch member adapted to engage selectively one or the other of said pair of clutch members when in either of its two driving positions, gearing connected to said traction means, and traction gearing driving clutch means carried in part by said traction means gearing and in part by said shiftable sleeve and operable to provide a driving connection between said electric motor and said traction means when said shiftable sleeve is in one driving position, in which one driving position a driving connection is also provided by the first named clutch means on said shiftable sleeve and one of said pair of clutch members, said traction gearing driving clutch means being disengaged when said shiftable sleeve is in its neutral position and when it is in the other of its driving positions.
